Primary Examiner—Louis S. Zarfas*Assistant Examiner*—G. Andoll*Attorney, Agent, or Firm*—Fulwider Patton Lee & Utecht, LLP[57] CLAIM

The ornamental design for a shoe upper, as shown and described.

DESCRIPTION

FIG. 1 is a left hand view of a grinding shoe upper showing my new design;

FIG. 2 is a right hand view thereof;

FIG. 3 is a front view thereof;

FIG. 4 is a rear view thereof; and,

FIG. 5 is a top plan view thereof.

The broken line showing the sole in FIG. 2 is for illustrative purposes only and forms no part of the claimed design.
